HOWARD E. CAVANAH AND MATHEW G. SCHOLL, OF SANTA BARBARA, CALIFORNIA.

BLOCK-MAKING MACHINE.

1,383,526.

Specification of Letters Patent.

Patented July 5, 1921.

Application filed May 24, 1920. Serial No. 383,939.

To all whom it may concern:

Be it known that we, HOWARD E. CAVANAH and MATHEW G. SCHOLL, citizens of the United States, residing at Santa Barbara, in the county of Santa Barbara and State of California, have jointly invented new and useful Improvements in Block-Making Machines, of which the following is a specification.

10 This invention relates to block making machines, and particularly to concrete block making machines for forming hollow blocks. The invention comprises in the main a fixed member and a movable member. A mold or die is detachably joined to the movable member and sectional cores are arranged to divide the mold into compartments. The cores are likewise detachably joined to the movable member. The mold is preferably 15 rectangular in form and is provided with side and end walls and is open at what might be termed the top or base. The interior surface of the side and end walls of the mold are angularly disposed to each 20 other,—that is to say, the mold box or block has its end members and side members so joined to each other that the members are spaced wider at the bottom than at the top, so that the wall members seem to diverge 25 from the top downwardly or converge from the bottom upwardly. Each of the core members has its side walls arranged at angles to each other, and from what would be termed the top of the core member the 30 walls would converge downwardly. A pad placed on the fixed member and conforming to the configuration made by the core members and the sides of the block member fits between the core member and the side walls 35 of the mold. Concrete is then poured into the open space between the block mold and the core members. A rack is fastened to the movable member and a bracket supporting a segment gear is fastened to the fixed member, and handle means is attached to the 40 segment so that when the handle is revolved the segment meshing with the rack will cause the movable member to move relatively to the fixed member. When this is 45 done any concrete within the spaced portions will be forced outwardly and left standing in the form of the block.

The main object of this invention is to 50 reduce labor cost in the manufacture of hollow blocks by a machine of this character

which may be operated by one man. A further object is to reduce hand-tamping and to form a firmer block having a harder back than heretofore. It will be understood that forcing the movable member down over the 60 fixed member, will cause the concrete to pack, for the walls between the cores and the mold block being angularly disposed to each other will tend to force the concrete downwardly and grip it. This gripping action 65 and pressing action tends to force the cement in the concrete to the surface with the result that a harder block or weather-resisting block is made. Likewise the concrete can be used in a wetter state than is ordinarily possible. It is a known fact that Portland cement is most satisfactory when used with a great deal of water, and this block machine is particularly suited for the use of Portland cement. After the movable 70 member has moved downwardly a sufficient distance leaving the concrete block upstanding, the pad which fills the bottom space between the cores and the sides of the block mold, may be readily removed and carried 75 to a suitable place for drying the block, and another pad placed within the mold block.

In practising the invention it has been found that movement of the movable member downwardly a slight distance, then tapping the concrete slightly and brushing off the residue even with the core and the block member, will form a harder concrete block 80 of more uniform height.

The invention has for further objects the 85 provision of an improved block machine which will be superior in point of relative simplicity and inexpensiveness, taken in conjunction with compactness in form and attractiveness in appearance, durability, and 90 positiveness and reliability in action, as well as general efficiency and serviceability.

With the above and other objects in view, the invention consists in the novel and useful provision, formation, construction, combination, association, and inter-relation of parts, members and features, all as herein-after described, shown in the drawing, and finally pointed out in claims.

In the drawing:

Figure 1 is a fragmentary elevation, certain parts being shown in section, of an improved block making machine, and taken on the line x^1-x^1 , Fig. 3;

Fig. 2 is a fragmentary cross sectional

view of the machine shown in Fig. 1, and taken on the line x^2-x^2 , Fig. 1, and looking in the direction of the appended arrows;

Fig. 3 is a cross sectional top plan view 5 of the device shown in Fig. 1, and taken on the line x^3-x^3 , Fig. 1; and

Fig. 4 is a perspective view of a concrete block made by the block making machine.

Corresponding parts in all the figures are 10 designated by the same reference characters.

Referring particularly to the drawing, A designates a side supporting frame member, B a side frame member for holding a block mold, C a block mold, D core members, E a beam to which is attached the core members D, F a standard to which the beam E and the movable member B are slidably arranged relative thereto, G spacer members for maintaining the block mold C in position, and H pads removably resting upon the stand F and within the space formed by the interior wall surface of the block mold C and the exterior surfaces of the cores D; all of which elements are used in practising 25 one embodiment of the invention.

The frame A is ordinarily embedded in or attached to some base material or member, as at 1, so that the frame is held rigidly upward. Likewise the frame member or 30 standard F is also embedded in the material 1 and in addition the frame member F is provided at its lower portion as at 2, with inwardly projecting parts 3, which parts incase along with the interior portion 4 a block 35 member 5. This particular construction insures a maximum of rigidity. Attached to the frame member A as at 6 are brackets 7. These brackets are held in position to the frame member A by means of bolts 8. A journal 40 9 is provided on the brackets as at 10 and a shaft 11 is supported within the journals. As will be observed by referring to Fig. 1 the shaft extends transversely between each of the frame members A.

The side frame members B which are 45 used in connection with the block mold or die C are provided at each end with filler members 12, which filler members extend transversely between the members B. Bolts 50 13 hold the filler members 12 in position. Ring brackets 14 are joined to the filler members 12 and held in position thereto by means of bolts 15.

The beam E is likewise provided at each 55 end with ring brackets 16 held to said beam by means of bolts 17. The ring brackets 16 are similar to the ring brackets 14 mounted upon the filler member 12.

Attached to the members A as at 18 and 60 19 are outstanding cup-shaped bracket members 20, which chambered portion of the cup-shaped bracket members 20 have contained therein guide rods 21, which rods are parallel with and spacedly arranged 65 from the frame members A, as shown in

the drawing. The ring brackets 14 and 16 which are joined to the members 12 and E are so arranged that they slide coaxially upon the guide rod members 21, so that the side frame members B and the beam E may move upwardly or downwardly dependent upon certain other mechanism. Racks α 70 are joined to one of the frame members B and near the ends thereof, as at 22, by means of the bolts 13 which pass through the filler members 12. Keyed to the shaft 11 as at 23 are segment gears 24. Each of the brackets 7 is provided with intermediate spacers 25 joined to the bracket arms 7 by means of bolts. Idlers 26 are rotatably mounted intermediate the members 25 and the teeth of the idlers 26 mesh with the teeth of the segment 24 and the rack α . Intermediate the shaft 11 and fixedly joined thereto as at 27 is a lever 28. A movement of the lever 85 downwardly in the direction of the arrow shown in Fig. 2 will cause the rack α to likewise move downwardly, and inasmuch as the rack is joined to the beam E and the side members B, the side members B and the beam E will move downwardly. The side members B support between them a concrete block mold C, which block mold is provided with end extensions 29 between which extensions extend spacer members 30 95 and these spacer members 30 and the block mold extension portions 29 are rigidly held to the side members B by means of transverse bolts 31 passing through said members. The block mold or die is so formed 100 that the top of same is slightly narrower than the bottom; that is to say, the side walls 32 and end members 33 are all arranged at an angle to each other, and which angle would be convergently downward, thus making the base portion of said block mold or die wider than the top portion; in other words, it is in the form of a hollow 105 frustum of a square or rectangular pyramid.

Each of the core members D is likewise in the form of a frustum of a square or rectangular pyramid, but with the base portion extending upwardly or just the reverse in the case of the block mold C. This causes 115 the various wall portions of both the core members D and the interior surfaces of the block mold C to converge toward one another at the top and to diverge near the base thereof. For clearness, the showing in the 120 various figures has been purposely exaggerated to show this condition. Each of the core members D is provided with an extension which is integrally formed, which extension need not have angularly disposed 125 walls, and which extension is joined to the beam E as at 34 by means of bolts 35.

The stand F extends upwardly a sufficient distance so that the end portions of the same as at 36 may serve to support a pad H. 130

Portions of the stands F are longitudinally slotted as at 38 to accommodate certain of the bolt members 35 which hold the cores D to the beam E. Other slotted portions 5 as 39 are merely arranged so as to brush off any concrete that might fall on top of the beam E, so that it could not harden there and clog the machine.

The pads H are preferably made T-shaped 10 in cross section in order to allow the fingers to grip an edge 37 of same when it is desired to move the pad with the concrete block resting thereon from the top 36 of the stands F. The pads H are so designed 15 that they completely fill the space formed by the inside walls of the block mold C and the outer wall surfaces of the cores D, so that when concrete 40 is poured into the intervening space formed by the cores D and 20 the block mold C, the concrete will be retained therein and prevented from escaping by the top surface of the pad H. In other words, the pad acts as a base member.

Revolving the handle 28 in the direction 25 shown by the arrow in Fig. 2 will cause the rack a to move downwardly and inasmuch as the frame members B and the beam E are joined to said rack the core members D and the block mold C will tend to move 30 downwardly in step with the rack a while the pad H supported as at 36 on the stand F will remain stationary, thus forcing any concrete that may be contained within the spaced portions formed by the cores D and 35 the side walls of the block mold C, upwardly, and leave an upstanding block similar to that shown in Fig. 4. Quite obviously if the wall portions were given as much angle as is shown in the figures, it would 40 be impossible for the pad H to move between the open spaces, but in actual practice the pad is made of a width corresponding with the width of the top of the mold C and the cores D, so that this objection is readily 45 overcome.

The reason for the slotted portions 38 in the stand F is now obvious, inasmuch as the bolt members 35 holding the core D to the beam E could not move downwardly unless 50 there are slots as shown. In addition the stands F coöperate with the guide rods 21 and serve to make the movable members rigid in their movement, with little or no play so that when the handle means 28 is 55 turned there will be a uniform downward movement of all parts. The handle means 28 of course might be put at one end of the shaft, but it has been found that by placing the handle means intermediate the shaft, as 60 shown in Fig. 1, the torsion upon the shaft 11 is equal in both directions and a more uniform movement of the movable members is obtainable.

In certain cases it has been found desir- 65 able to make a portion of the core members

D with the opposite sides as y and z parallel for a short distance, and then to have the side surfaces converge downwardly, as has been explained. By having the parallel sides y and z, a movement of the cores and 70 the block mold C downwardly a short distance allows the plastic material 40 to move in relation to said cores and block mold more easily, without breaking or unevenness. Slightly tapping the concrete then brushing 75 the residue off, allows, when a further movement of the cores and the block mold C are moved under action of the lever 28, to form concrete blocks of more uniform height. 80

The operation is as follows:

If it is desired to form a concrete block similar to that shown in Fig. 4 having a certain number of hollow portions, as shown, the cores D would be detachably joined by 85 means of the bolts 35 to the frame member E, and the block mold C would be detachably joined to the frame member B by the bolts 31. A pad H would be placed within the spaced portions formed by the cores D 90 and the sides of the block mold C, so that a leg portion as 41 would rest upon the top surface 36 of the stand F. After this is done the handle 28 would be revolved upwardly so that the device would be ready 95 for pouring concrete within the spaced portions. After concrete 40 completely filled the intervening spaced portion the handle 28 would be revolved downwardly a short distance and the concrete tapped slightly 100 and then the excess brushed off and the handle completely revolved downwardly, so that the block would stand in position for removing from the machine. The particular 105 sloping surfaces of the cores and the block mold would give a squeezing effect to the concrete and tend to pack and trowel the sides of the block bringing the cement to the surface. The pad H with the upstanding concrete block would then be removed 110 from the machine and carried to a place for drying, and another pad could be inserted and the operation repeated at will.

It is manifest that many variations and changes may be made, with respect to the 115 disclosure of the foregoing description, and the accompanying drawing, in adapting the invention to varying conditions of use and service, without departing from the true spirit of the invention.

Having thus disclosed our invention, we claim and desire to secure by Letters Patent:

1. A device for forming concrete blocks, comprising a mold having side and end walls, a core within the mold, a pad set in 125 said open space out of contact with the compartment walls thereof, and means whereby the pad is capable of being passed therethrough; said core being formed with means for compressing material in the mold. 130

2. A device for forming concrete blocks, comprising a mold having side and end walls, a core within the mold; a removable pad within the space formed by the mold and core, a support for said pad, and means for causing said mold and core to move relatively to said pad; said core being formed with means for compressing material in the mold.
- 10 3. A device for forming concrete blocks, comprising a mold having side and end walls, a core within the mold, a pad set in said open space out of contact with the compartment walls thereof, means whereby the core and mold are movable relatively to the pad in an axial direction; said core and mold being formed so as to compress material in the mold when the core and mold move relatively to the pad.
- 15 4. A block-making machine, comprising a mold, a core disposed within the mold casing, and a removable pad within the mold casing; a member detachably holding said mold, and a member to which said core is detachably joined; a frame, and means for slidably mounting said last named members to said frame, whereby the core and mold may be moved together relative to the pad leaving an upstanding block formed by the mold; said core being formed with means for compressing the material in the mold.
- 20 5. A device for forming blocks, comprising a mold having side and end walls which are angularly arranged to each other, a removable pad closing the bottom of said mold, and means for causing said mold to move so as to pass the pad therethrough, whereby plastic material contained within the mold and supported by the pad will be squeezed inwardly and downwardly by the angularly disposed walls and caused to pack.
- 25 6. A device for forming blocks, comprising a mold having side and end walls which are arranged angularly to each other, a removable pad closing the bottom of said mold, and a core arranged to divide the mold into compartments, and means for causing said mold and core to move so as to pass the pad therethrough, whereby plastic material contained within the mold and supported by the pad will be squeezed inwardly and downwardly by the angularly disposed walls and caused to pack.
- 30 7. A device for forming blocks, comprising a mold having side and end walls, a core within the mold, the walls of which are angularly disposed to each other, a removable pad closing the bottom of said mold, and means for causing said core and mold to move so as to pass the pad therethrough, whereby any plastic material contained within the mold and supported by the pad will be squeezed inwardly and downwardly by the angularly disposed walls and caused to pack.
- 35 8. A device for forming blocks, comprising a mold having side and end walls and a core within the mold, the walls of said mold being divergently disposed from the top to the base, a removable pad closing the bottom of said mold, and means for causing said mold and core to move so as to pass the pad therethrough, whereby plastic material contained within the mold and supported by the pad will be squeezed inwardly and downwardly by the angularly disposed walls and caused to pack.
- 40 9. A device for forming hollow blocks, comprising a mold having side and end walls divergently disposed to each other from the top to the base, a core within the mold, the walls of which are convergently disposed to each other, a pad set in the open space out of contact with the compartment walls thereof; means being provided whereby the core and mold are movable relative to the pad in an axial direction.
- 45 10. A device for forming hollow blocks, comprising a mold having side and end walls divergently disposed to each other from the top to the base, a core within the mold, the walls of which are convergently disposed to each other, a pad set in the open space out of contact with the compartment walls thereof; means being provided whereby the core and mold are movable relative to the pad in an axial direction, so that any plastic material contained within the mold and supported by the pad will be squeezed inwardly and downwardly of the angularly disposed walls and caused to pack.
- 50 11. A block-making machine comprising a mold, a core disposed within the mold casing, and a removable pad within the mold casing; a member detachably holding said mold, and a member to which said core is detachably joined; a frame support provided with spaced guide rods, means joined to the member supporting said mold and the guide rods, whereby said member may be moved relatively to said frame support; and means joining the member to which the core is attached with the guide rod; a rack disposed between said member holding the mold and the member holding the core; bracket members mounted upon the frame support, a shaft mounted in bearings joining said bracket members, a segment keyed to said shaft, an idler meshing with the teeth of said segment and said rack and a handle fixedly mounted upon said shaft, whereby upon movement of said handle the members holding the core and mold are caused to move downwardly or upwardly upon the guide means.
- 55 12. A block-making machine, comprising a mold casing, a core disposed within the mold casing, a member detachably holding said mold, and a member to which said core is detachably joined; a frame support pro-

vided with spaced guide rods, means joined to the member supporting said mold and the guide rods whereby said member may be moved relatively to said frame support; 5 and means joining the member to which the core is attached with the guide rod; racks disposed between said member holding the mold and the member holding the core; bracket members mounted upon the frame support, a shaft mounted in bearings joining said bracket members, segments keyed to said shaft, an idler meshing with the teeth of said segments and said racks and a handle fixedly mounted upon said shaft, whereby upon movement of said handle the members holding the core and the mold are caused to move downwardly or upwardly upon the guide means; there being a removable pad disposed within the mold casing and forming a base for said mold casing.

13. A block-making machine comprising a mold, a core disposed within the mold casting, a member detachably holding said mold, 25 and a member to which said core is detachably joined; a frame support provided with spaced guide rods, means joined to the member supporting said mold and the guide rods whereby said member may be moved relatively to said frame support; and means joining the member to which the core is attached with the guide rod; racks disposed between said member holding the mold and the member holding the core; bracket members mounted upon the frame support, a shaft mounted in bearings holding said bracket members, segments keyed to said shaft, an idler meshing with the teeth of said segments and said racks and a handle fixedly mounted upon said shaft, whereby upon movement of said handle the members holding the core and the mold are caused to move downwardly or upwardly upon the guide means; there being a removable pad disposed within the mold casing and forming a base for said mold casing.

14. A block-making machine comprising a mold, cores disposed within the mold casting, a member detachably holding said mold, and a member to which said cores are detachably joined; a frame support provided with spaced guide rods, means joined to the member supporting said mold and the guide rods whereby said member may be moved

relatively to said frame support; and means joining the member to which the cores are attached with the guide rod; racks disposed between said member holding the mold and the member holding the cores; bracket members mounted upon the frame support; a shaft mounted in bearings holding said bracket members, segments keyed to said shaft, idlers meshing with the teeth of said segments and said racks and a handle fixedly mounted upon said shaft, whereby upon movement of said handle the members holding the cores and mold are caused to move downwardly or upwardly upon the guide means; there being a removable pad T-shaped in cross section disposed within the mold casing and forming a base for said mold casing; said pad being out of contact with the walls thereof and adapted to move relatively within the compartments formed by the core members and the mold in an axial direction; and a rigid supporting means for holding said pad within the compartments.

15. A device for forming concrete blocks, comprising a mold having side and end walls, a core within the mold, the walls of which core have their opposite side outer surfaces parallel for a short distance and then the remaining wall distances are angularly disposed to each other, a removable pad closing the bottom of said mold, means for causing said core and mold to move so as to pass the pad therethrough, whereby any plastic material contained within the mold and supported by the pad will be squeezed inwardly and downwardly by the angularly disposed walls and caused to pack.

16. A device for forming hollow blocks, comprising a mold having side and end walls divergently disposed to each other from the top to the base, a core within the mold, the walls of which are parallel for a short distance near the top of the core, and then are convergently disposed to each other the remaining distance, a pad set in an open space out of contact with the compartment walls thereof; means being provided whereby the core and mold are movable relative to the pad in an axial direction.

In testimony whereof, we have signed our names to this specification in the presence of two subscribing witnesses.
